UNITED STATES PATENT OFFICE.

CARL M. PAGE, OF GENEVA, ILLINOIS, ASSIGNOR TO GEORGE FABYAN, OF GENEVA, ILLINOIS.

APPARATUS FOR CRACKING OIL.

Application filed March 22, 1922. Serial No. 545,766.

It is an object of this invention to produce an auxiliary heating device for use within a still.

It is a further object of this invention to provide for gradually heating the oil vapors from a temperature just below that of cracking to the cracking point and permitting the cracked vapors to cool again to a temperature slightly below the cracking point.

It is a further object of this invention to control the flow of vapors past the heating device in such a way that a sudden expansion of the vapors shall occur just after the point of maximum heating is passed.

It is a further object of this invention to provide an auxiliary heating device for an oil still with means leading from outside the still for supplying the heat.

Other and further important objects of this invention will be apparent from the disclosures in the specification and the accompanying drawings.

The invention (in a preferred form) is illustrated in the drawings and hereinafter more fully described.

On the drawings:

Figure 1 is a view, partly in section, of a still with this invention applied thereto.

Figure 2 is a vertical section through the auxiliary heating device.

Figure 3 is a section upon the line 3-3 of Figure 2.

As shown on the drawings:

The still includes the usual boiler-shaped receptacle 1 set over a furnace 2 which has the usual stack 3. The still has the usual outlet pipe 4. In the top of the still are a number of domes or caps 5 which serve to support the auxiliary heating devices which constitute the subject of this invention. As illustrated, there are two such caps shown and two such auxiliary heaters used; but any number may be used, depending upon the size of the still and the rapidity with which it is worked.

The caps 5 serve to support the auxiliary heaters in any desired fashion. As illustrated, the top of each cap is a plate 6 which supports a sleeve 7 surrounding the stack 8 which leads away from the auxiliary heater. The stack is supported from the sleeve in any desired fashion and the sleeve serves to hold the lower end of the stack in the proper position. Entering each stack at a

point a little above the top of the still is a pipe 9 for supplying air. Air is driven through this pipe from any desired source of supply, such as a blower. An oil pipe 10 enters through the wall of the pipe 9 and continues inside the pipe 9 to the point 11 where the pipe 9 is joined to a funnel-shaped mouth 12 which is continued by a cylindrical chamber 13. The pipes 9 and 10 are controlled by suitable valves to regulate the flow of oil and air. The stack 8 is continued by a flaring end 14 which joins the cylindrical wall 15 that constitutes the outside of the combustion chamber.

Oil emerging from the end of the pipe 10 at the point 11 mingles with air from the pipe 9 and is ignited in any desired way. The flame emerges from the lower end of the cylinder 13 and plays against the curved surface 16 of a body of refractory material, which closes the lower end of the combustion chamber. The material used should be a poor conductor of heat. Fire clay or some similar substance may be used. This body 17 is held in place by a plate 18 integral with the walls 15 and closing the lower end of the cylinder. A similar body of fire clay 19 fills the space between the cylindrical wall 15 and the conical wall 14. This body is covered over by a top plate 20 which may also be secured to the walls 15.

The funnel 12 and the cylinder 13 are secured in position by bolts or rivets 21. The bolts 21 pass through spacing blocks 22 which serve to separate the cylinder 13 from the outer wall 23 of the auxiliary heater. The bolts 21 also serve to support this outer wall. The passage between the cylindrical wall 15 and the wall 23 is constricted near the lower end of the wall 23 by an oblique projection 24, the upper end of which is shown in the drawing as coming opposite the lower end of the cylinder 13. The proper position of the upper end of this obstruction depends upon the conditions met in any particular still. It should be located opposite the point at which the wall 15 is heated to the highest temperature. The upper end of the obstruction 24 is an annular flange 25 so that the passage 30 between the walls 15 and 23 is first gradually narrowed and then abruptly widened to its full width.

In the operation of this device, the oil in the still 1 is heated by the fire in the fur-

nace 2 until it reaches nearly the cracking point. The vapors arising from the heated oil before this point is passed, pass off through the outlet 4. As the cracking point is neared, the valves in the pipes 9 and 10 are opened and the oil mingled with the air in the chamber 12-13 is lighted so that the space above the body 17 is filled with flame. The mixture of oil and air passes down the funnel 12 and begins to burn within the cylinder 13. The velocity of the entering air is increased by the velocity of the flame so that the flame plays against the surface 16 with considerable force and is deflected and comes against the walls 15, heating them partly by direct contact of the flame and partly by reflected heat from the surface 16. The result is that the walls gradually increase in temperature from the point where the surface 16 meets the walls, to a point a little higher above, and then slowly and gradually decrease in temperature to the beginning of the funnel 14. Part of the heat due to the burning will be reflected back into the combustion chamber and the funnel 14 thus protects the upper portion of the walls 15 from the full force of such heat. The fireclay 19 affords additional protection to the upper part of the walls 15; consequently, from the point at the beginning of the funnel 14 to the upper end of the walls 15, the decrease in temperature is more rapid. Such heat as remains in the products of combustion when they enter the stack 8 serves to partly vaporize the oil in the part of pipe 10 inside of the stack so that the flame is readily maintained.

Oil vapors in the still 1 are drawn into the passage 30 between the walls 15 and 23 by convection, they pass up the narrowing passage between the obstruction 24 and the walls 15, and are heated as they pass, so that at the moment of their highest temperature they are at the narrowest part of the passage. In the proper operation of the device, this is the cracking temperature. The vapors debouch from the narrow part of this passage into the full sized passage and are thus enabled to expand abruptly. This sudden expansion comes while they are at the cracking temperature, with the result that it assists materially in producing the cracking. The cracked vapors passing up the remainder of the passage are cooled not suddenly but gradually, with the result that the reactions can go on for a time after the point of maximum temperature is passed. This assists materially in the production of a compound closely resembling sweet gasoline, and the unsaturated compounds have ample opportunity to become changed during the gradual cooling. This action is materially assisted by making the surface of the wall 15 of catalytic material. Iron is itself a good catalyst for this purpose, but for cer-

tain oils the wall 15 may be of aluminum or may be covered with aluminum oxide to advantage. I do not however confine myself to these substances. The vapors which emerge from the top of the passage are therefore largely made up of gasoline. They emerge into the caps 5, which, being cooled by the outer air, cool the vapors still further, so that gasoline vapors cooled nearly to the point of condensation are finally delivered at the outlet 4.

It should be remembered that although heating and cooling are spoken of in describing the passage of the vapors between the walls 15 and 23, the total change in temperature during this passage is small. This is because the vapors enter this passage at nearly the cracking temperature. The heating done during this passage is to a point only slightly, if any, above the cracking temperature, and the cooling is to a point corresponding to the temperature of the still as a whole, which is slightly below the cracking temperature. The whole difference of temperature between the lower and upper ends of the passage through the auxiliary heater should be only just sufficient to maintain a convection current therethrough. This need not be as great as would otherwise be necessary since the cracking itself produces changes in the specific gravity of the vapors.

I am aware that numerous details of construction may be varied through a wide range without departing from the principles of this invention, and I therefore do not purpose limiting the patent granted otherwise than necessitated by the prior art.

I claim as my invention:

1. In a heating device for the vapor space of an oil still, two walls constituting a passage, an obstruction narrowing said passage relatively to other parts of said passage, means for locally heating one of said walls whereby said passage is at a higher temperature at a point adjacent said obstruction.

2. In a heating device for the vapor space of an oil still, two walls constituting a passage, an obstruction narrowing said passage, means for locally heating one of said walls whereby said passage is at a higher temperature at a point adjacent said obstruction, the area of said passage diminishing from the entrance thereof to the point of greatest obstruction and then abruptly enlarging to the full area of the passage.

3. In a heating device for the vapor space of an oil still, two walls constituting a passage, an obstruction narrowing said passage, means for locally heating one of said walls whereby said passage is at a higher temperature at a point adjacent said obstruction, the area of said passage diminishing from the entrance thereof to the

point of greatest obstruction and then abruptly enlarging to the full area of the passage, and the heated wall having a surface of catalytic material.

- 5 4. In an auxiliary heater for an oil still, a combustion chamber, an air pipe leading to said chamber, an oil pipe within said air pipe and also leading to said chamber, a pipe for the products of combustion leading away from said chamber, heat insulating means for confining the heat of combustion to a portion of the walls of said chamber, and a vapor conducting means surrounding said chamber.
- 10 5. In a heating device for the vapor space of an oil still, an air pipe, an enlargement at the end of said pipe means for admitting combustible material into said en-

large-
ment, a chamber surrounding said en-
large-
ment, a jacket surrounding said cham- 20
ber means extending through the walls of
said chamber for supporting said enlarge-
ment, said means also supporting said jacket.

6. In a heating device for the vapor space of an oil still, a cylindrical chamber, means 25
within said chamber for heating the same,
an external cylinder surrounding said cy-
lindrical chamber, a conical obstruction on
the interior of said external cylinder, where-
by an annular constricted opening exists in 30
the passage between the said concentric cyl-
inders.

In testimony whereof I have hereunto
subscribed my name.

CARL M. PAGE.
